DRAFT REGULATOR

James L. Breese, Santa Fe, N. Mex.

Application February 19, 1937, Serial No. 126,571

2 Claims. (Cl. 236—45)

My invention relates to an improvement in control dampers for use, for example, with oil burners.

One purpose is the provision of a damper for controlling the inflow of atmospheric air to a flue.

Another purpose is to render such inflow automatically responsive to variations of temperature adjacent the valve member of the damper.

10 Another purpose is the provision of an improved thermostatically operating damper member.

Another purpose is the provision of such a damper member which has a thermostatic control mounted on and movable with the valve member of the damper itself.

Other purposes will appear from time to time in the course of the specification and claims.

I illustrate my invention more or less diagrammatically in the accompanying drawing wherein:

Figure 1 is a side elevation;

Figure 2 is a section on the line 2—2 of Figure 1; and

Figure 3 is a partial section on the line 2—2 of Figure 1 on an enlarged scale, illustrating the parts in slightly different position.

Like parts are indicated by like symbols throughout the specification and drawing.

Referring to the drawing, I generally indicates

30 any suitable flue pipe or chimney which will be understood to extend upwardly or outwardly from any suitable combustion zone such as an oil burner, stove, or the like. Associated therewith is a laterally extending stub passage 2, the end of which is surrounded by a ring 3 herein shown as having an inwardly extending circumferential flange 4. The space within the aperture defined by said flange is normally enclosed, for example, by the valve member 5, herein

40 shown as provided with any suitable pin 6, the ends of which are received in bearings 7, 8 at opposite sides of the flange 4. 9 is any suitable stop or projection associated with the flange 4 and adapted to limit the rotation of the valve 5 in one direction. 10 is a weight tending normally to hold the valve 5 in closed position against the stop 9. It is shown as screw-threaded upon a screw-threaded pin 11 which is secured to the end of a thermostatic strip 12, the opposite end 50 of which is secured as at 13 to the valve 5. The valve 5 may be cut away as at 14 to conform generally to the contour of the weight 10. It will be understood that the weight 10 tends gravitally to resist opening of the valve 5 when the pressures in the flue 1 are below atmospheric.

The atmospheric pressure on the opposite side of the valve 5 moves it into open position as shown in Figure 3 and atmospheric air is allowed to pour into the flue. The baling or resisting effect of the weight 10 is varied in response to 5 changes of heat conditions in the flue. Assuming there is an increase in heat, the strip 12 may flex from the position in which it is shown in Figure 2 to the position in which it is shown in Figure 3, thereby moving the weight 10 inwardly 10 in relation to the valve 5 and reducing its tendency to hold the valve in closed position. This provides a definite increase in the flow of air allowed through the stub 2 into the flue 1 and thus a decrease of draft up the flue and therefore 15 a decrease of air inflow or air supply to the zone of combustion. As the temperature in the flue 1 drops, the strip 12 flexes in the opposite direction and the weight 10 becomes increasingly effective in closing the valve 5. The weight may 20 be manually adjusted in relation to the strip 12 by rotating it in relation to the screw-threaded stem 11.

It will be realized that whereas I have herein shown and described a practical operative device, 25 nevertheless many changes might be made in the size, shape, number and disposition of parts without departing from the spirit of the invention and I wish, therefore, that my showing be taken as in a sense diagrammatic.

30 For instance, the shape of the strip 12 may be widely varied. Where I describe the strip in the claims as a thermostatic strip, it will be understood that I mean a strip or member which flexes or changes its shape or position in such fashion 35 as to move the weight at its free end. It will be understood, of course, that the feature of adjusting the weight, while normally useful, may be dispensed with if desired.

40 I claim:

1. An automatic draft regulator for ducts or the like which includes an inlet member adapted to communicate with said duct, a valve member pivoted in said inlet member and adapted when in one position substantially to close the inlet 45 thereof, a thermostatic strip secured at one end to said valve member and a weight supported on the free end of said strip, said thermostatic strip lying closely adjacent the inner face of said valve member and being adapted to respond to changes 50 in temperature within said duct and thereby to move said weight in relation to said pivoted valve member.

2. An automatic draft regulator for ducts or the like which includes an inlet member adapted 55

to communicate with said duct, a valve member pivoted in said inlet member and adapted when in one position substantially to close the inlet thereof, a thermostatic strip secured at one end to said valve member and a weight supported on the free end of said strip, said thermostatic strip being positioned within the inlet member and be-

ing constantly exposed to temperature conditions within said duct, and being adapted thereby to move said weight in relation to said pivoted valve member, in response to temperature changes within said duct.

JAMES L. BREESE.
